FRAMING MODULE FOR LIGHTING FOR CEILINGS OR SIMILAR ARTICLE

Stuart H. Manley, White Bear Lake, Minn., and William H. P. Tacke, Wyoming, Mich., assignors to Conwed Corporation, St. Paul, Minn.

Filed Aug. 6, 1973, Ser. No. 386,071

Term of patent 14 years

Int. Cl. D26—05

U.S. Cl. D48—7 D

FIG. 1

FIG. 2

FIG. 3

FIG. 1 is a bottom perspective view of a framing module for lighting for ceilings or similar article showing our new design;

FIG. 2 is a cross-sectional view taken on line 2—2 of FIG. 1;

FIG. 3 is a cross-sectional view taken on line 3—3 of FIG. 1.

The dominant feature of our design resides in the parabolic shape of the side and end walls.

We claim:

The ornamental design for a framing module for lighting for ceilings or similar article substantially as shown and described.
